ELEVATOR TABLE

John V. Hill, Los Angeles, Calif.

Application: May 14, 1951, Serial No. 226,244

3 Claims. (Cl. 254—9)

This invention comprises novel and useful improvements in an elevator table and more specifically pertains to a vertically adjustable appliance adapted to be rolled under an automobile and elevated to support the transmission case or other parts of the vehicle to facilitate the handling and removal of the same.

The primary object of this invention is to provide a mobile elevator table which may be readily raised or lowered and which shall be of a sufficient size and construction to enable the same to be employed beneath motor vehicles for raising and lowering transmission cases and the like to enable the manipulation and easy handling by a single workman as when applying or removing the cases.

A further object of the invention is to provide an appliance as set forth in the foregoing object which shall have improved means for controllably raising or lowering the same.

Yet another object of the invention is to provide an apparatus in conformity with the foregoing objects, wherein improved means are provided for effecting the raising and lowering movement without interfering with the mobility of the device.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a side elevational view of one embodiment of apparatus in accordance with this invention, the same being shown in its collapsed or folded position in full lines and in its elevated or operative position in dotted lines;

Figure 2 is a top plan view of the apparatus of Figure 1, the top tray or platform being removed therefrom, certain parts being shown in horizontal sectional view;

Figure 3 is a vertical transverse sectional view taken substantially upon the plane indicated by the section line 3—3 of Figure 2, the device being shown in its collapsed position;

Figure 4 is a vertical transverse sectional detail view taken substantially upon the plane indicated by the section line 4—4 of Figure 2; and

Figures 5 and 6 are perspective views of two beams forming part of the carriage of the adjusting mechanism of the invention.

Referring now more specifically to the accompanying drawings, wherein like numerals designate similar parts throughout the various views, it will be seen that the device consists essentially of a tray-like mobile base 10 which may be provided with castor rollers or the like 12, together with a tray-like platform 14 and an adjustable connecting linkage between the platform and tray for vertically adjusting the former with respect to the latter.

Adjacent each of its four corners, the tray 14 upon its undersurface is provided with depending lugs 16 while similarly positioned upstanding lugs 18 are appropriately positioned upon the top surface of the base 10. These lugs are pivotally connected to the above mentioned operating linkage whereby the platform is adjustably connected to the base.

As will be now better understood, sets of articulated or hinged legs are provided connecting the sets of complementary lugs 16 and 18. Each of the articulate or hinged legs is disposed in a plane which is parallel to those of the other legs. The two legs upon each side of the device, at what may be termed the front and back corners

2

of the same, are disposed more closely adjacent to each other than they are to the two legs upon the other side of the device.

It will be readily understood that the leg assemblies for the two sides of the device are of identical construction, so that a description of one will be sufficient for an understanding of the other. Referring, therefore, more particularly to Figures 1 and 2, it will be seen that each such leg assembly comprises a forward leg and a rearward leg, the forward leg consisting of upper and lower leg members 20 and 22 which have their adjacent ends hinged to each other as set forth hereinafter, and which have their opposite ends pivoted, as at 24, and 26 to the lugs 16 and 18 of the platform and base respectively at the front ends thereof. Similarly, the rearward leg assembly includes upper and lower leg members 28 and 30 having their adjacent ends hinged pivotally to each other as set forth hereinafter, and having the opposite ends pivoted as at 32 and 34 to the upper and lower lugs 16 and 18 of the platform and base respectively. The front and rear leg assemblies of each side are so disposed that their hinged ends overlap each other as shown in Figure 1. It will now be apparent from Figure 1 that as the upper and lower leg members of each of the hinged legs are moved toward a straight line position, the platform 14 will be elevated or raised with respect to the base 10, until such time as the leg members are in vertical line, at which time the platform will be at its maximum elevation. Alternatively, as the leg members are moved away from this vertical straight line position, the platform will be lowered with respect to the base until such time as the leg members are completely folded upon themselves, as shown in full lines in Figure 1, and in Figure 3, at which time the platform will be at its most collapsed or lowered position.

Each of the hinged legs is provided with a bracing construction. Thus, a pair of links or braces 36 and 38 have their opposite ends pivoted, as at 40 and 42, respectively, with the intermediate portions of the upper and lower leg members 20 and 22, and have their adjacent ends pivoted to each other as set forth hereinafter. Similarly, corresponding braces 44 and 46 are provided for the rear leg assemblies, these braces having their opposite ends pivoted intermediate the ends of the upper and lower leg members 28 and 30 as at 48 and 50 respectively, while the adjacent ends of the braces are pivoted to each other as set forth hereinafter.

The above described construction is, of course, duplicated upon both sides of the device, as will be readily understood from Figures 2 and 3.

The various pivotal connections of the upper and lower leg members, and of the adjacent ends of the braces are secured to an adjusting mechanism whereby all of the leg members and braces will be simultaneously operated to evenly distribute the load during the raising or lowering of the platform with respect to the base. This operating mechanism includes a carriage which is mounted upon the pivotal connections of the leg members and braces for vertical movement therewith during operation of the same. As shown in Figures 5, 6 and Figure 2, the carriage includes a pair of rigid beams 52 and 54. The beam 52 which may be termed the head beam of the carriage is provided at each end with a pair of laterally extending parallel brackets 56, 58 and 60, 62, these brackets having aligned bores for rotatably journaling a crank shaft 64, as shown in Figure 2, and which is provided with a manual operating handle 66. Upon opposite sides of the brackets 58 and 60, the crank shaft 64 is provided with pairs of driving gears 68, 70 and 72, 74. The gears may conveniently comprise beveled gears as shown and the gears of each pair are oppositely disposed.

The beam 52 is provided with pairs of bearing apertures 76, 78 and 80, 82. These four bearing apertures rotatably journal, receive and retain the ends of four screw threaded adjusting shafts or adjusting rods 84, 86 and 88, 90, respectively.

The other beam 54 is provided with four bearing apertures 92, 94 and 96, 98 which similarly receive and journal the other ends of these four adjusting rods. The four adjusting rods thus serve to retain the beams 52 and 54 in a substantially rigid assembly with respect to each other, to form the adjusting carriage of the device.

The adjusting rods, upon their ends which extend through the journaled apertures in the beam 52 are provided with beveled driven gears 100, 102 which respectively mesh with the driving gears 68 and 70, and 104, 106 which respectively mesh with the gears 72 and 74.

As will be readily seen from Figure 2, the arrangement of the driving and driven gears is such that the adjusting shafts 84 and 90 will be driven in the same direction while the adjusting shafts 86 and 88 will be driven in a reverse direction.

Carrier nuts are internally threaded for traveling movement upon the adjusting rods, which carrier nuts are of substantially the same construction, one such nut being indicated in Figure 4. This carrier nut comprises a body portion 108 internally threaded for engagement upon one of the adjuster rods such as the rod 90, the nut having a laterally extending pivot pin 110 having an externally threaded end portion 112 receiving a locking nut 114. These carrier nuts and their pivot pins thus serve to pivotally connect the adjacent ends of the upper and lower leg members 20, 22 and 28, 30 and operatively connect them to their respective adjuster rods. The adjacent ends of the braces 36, 38 and 44, 46, in addition to being pivotally connected to one another, are also pivotally connected to the lugs 83 and 85, respectively, on the carriage beams 52 and 54. As shown in Figure 4, suitable spacer members 116 may be provided upon the pivot pins 110 where needed to insure proper spacing of the various leg members and braces to permit the desired folding movement. As shown in Figures 5 and 6, laterally extending studs 87 project from the lugs 83 and 85 and may serve as the means for pivoting the adjacent ends of the braces to the carriage.

From the foregoing, it will now be seen that upon manual rotation of the shaft 64, each of the adjusting rods will be simultaneously rotated. The two rods at each side of the device will be rotated in opposite directions whereby the front and rear hinged legs will be moved in opposite directions as will be apparent from Figure 1 to effect the desired raising and lowering of the platform by the folding or straightening of the articulated legs.

It will be appreciated that the platform 14 constituting a tray will serve to support a transmission case or other member and properly adjust the elevation of the same during the manipulation of the member by the mechanic.

In its folded position, the device may readily be moved under a vehicle, may then be erected to bear against the undersurface of the transmission casing, whereupon, after the latter has been unbolted from the rest of the vehicle structure, the device may be lowered and the casing may be removed from beneath the vehicle for further handling.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. An elevator table including an upper platform, a base, a carriage interposed between said base and said platform and extensible and collapsible means interconnecting said platform, base and carriage, said means maintaining said base, carriage and platform in close proximity to one another in collapsed position and in spaced apart relation to one another in extended position, said carriage comprising a rectangular frame including a pair

of spaced apart beams, a pair of adjacent, parallel, threaded rods journaled at each end of said beams and extending therebetween, traveling nuts on said rods, said extensible and collapsible means including sets of legs, the legs of each set being hinged together and to one of said traveling nuts at their adjacent ends and to said base and platform at their opposite ends, one traveling nut being disposed on each of said rods.

2. An elevator table comprising a mobile base, a platform, a carriage interposed between said base and platform, sets of legs, the legs of each set being hinged together and to said carriage at their adjacent ends and to said base and platform at their opposite ends, the hinged connections of said sets of legs being arranged for horizontal movement in vertically parallel paths, said carriage including means for causing pivoting movement of said sets of legs for raising and lowering said platform and carriage upon said base, each set of legs having a pair of braces terminally pivoted to said legs intermediate the ends of the latter and to each other and to said carriage at their adjacent ends, said means for causing pivoting movement including a plurality of rotatably journaled rods, the hinged connection between the legs of each set being operatively connected to one of said adjusting rods, said adjusting rods having driving gears, a manually operable crankshaft journaled on said carriage and having driving gears in mesh with the adjusting rod gears for simultaneous operation thereof whereby rotation of said adjusting rods moves the legs of each set from a position longitudinally closely adjacent to one another to a position wherein the legs are substantially axially aligned with one another.

3. An elevator table including an upper platform, a base, a carriage interposed between said base and said platform and extensible and collapsible means interconnecting said platform, base and carriage, said means maintaining said base, carriage and platform in close proximity to one another in collapsed position and in spaced apart relation to one another in extended position, said carriage comprising a rectangular frame including a pair of spaced apart beams, a pair of adjacent, parallel, threaded rods journaled at each end of said beams and extending therebetween, traveling nuts on said rods, said extensible and collapsible means including sets of legs, the legs of each set being hinged together and to one of said traveling nuts at their adjacent ends and to said base and platform at their opposite ends, one traveling nut being disposed on each of said rods, each set of legs having a pair of braces terminally pivoted thereto intermediate the ends of the legs and the free ends of the braces of each pair of braces being pivoted to each other and to one of said beams.
